RADIO SPEAKER GRILL

Alexander Rauchman, New York, N. Y.

Application October 11, 1956, Serial No. 43,327

Term of patent 7 years

(Cl. D56—4)

Fig. 1 is a front elevational view of a radio speaker grill showing my new design.

Fig. 2 is a sectional view taken along a line 2—2 of Fig. 1.

The edges and rear of the speaker grill are substantially plain and unornamented.

I claim:

The ornamental design for a radio speaker grill, as shown and described.
